Patented July 24, 1973

227,896

INTER-DENTAL FLOSSING DEVICE

Ingram S. Chodorow, 100 E. Hartsdale Ave.,
Hartsdale, N.Y. 10530

Filed May 17, 1972, Ser. No. 254,345

Term of patent 14 years

Int. Cl. D24—99

U.S. Cl. D24—1 D

FIG. 4

FIG. 3

FIG. 1

FIG. 2

FIG. 1 is a top plan view of the inter-dental flossing device, the bottom plan view thereof is substantially identical;

FIG. 2 is a front elevation view thereof, the rear elevation view is substantially identical;

FIG. 3 is a left end elevation view thereof; and
FIG. 4 is a right end elevation view thereof.

I claim:

The ornamental design for an inter-dental flossing device, as shown and described.
